UNITED STATES PATENT OFFICE.

EDDY R. WHITNEY, OF LYNN, MASSACHUSETTS, ASSIGNOR TO GENERAL ELECTRIC COMPANY, A CORPORATION OF NEW YORK.

FRICTION-CLUTCH.

No. 853,849.

Specification of Letters Patent.

Patented May 14, 1907.

Application filed November 9, 1905. Serial No. 286,488.

To all whom it may concern:

Be it known that I, EDDY R. WHITNEY, a citizen of the United States, residing at Lynn, county of Essex, State of Massachusetts, have invented certain new and useful Improvements in Friction-Clutches, of which the following is a specification.

The present invention relates to power transmitting devices and more particularly to friction clutches, and the object of the invention is to provide a simple and highly efficient device of this character having provisions whereby the power for forcing the driving and driven clutch members into and out of engagement may be derived from the power transmitted instead of, as has been the usual practice heretofore, by the manual effort of the operator, or from other extraneous source of energy.

In carrying my invention into effect I provide a friction clutch in which the driving or driven member is adapted to be moved into or out of engagement with the other member, and on the driving member I mount a clutch actuating part so as to revolve positively therewith but capable of independent movement, and on some stationary part I mount a wedge or cam-shaped projection which is adapted to coöperate with the clutch actuating part as it revolves with the driving member to force the latter along its path of independent movement. The clutch actuating part is connected by suitable means to one of the clutch members so that its independent movement effects an axial movement thereof into or out of frictional engagement with the other clutch member. By positioning the stationary projection and the actuating part so that the latter engages the projection on one side of its leading apex, the clutch members will be caused to engage without further attention on the part of the operator, and by a slight change in the relative positions of the stationary projection and the revolving actuating part so as to cause the latter to engage the former on the other side of its apex, the clutch members will be automatically disengaged. The positioning of these parts may be accomplished by hand, electro magnets, or other simple means.

For a more complete understanding of the invention reference may be had to the following detailed description and the accompany-

ing drawings forming a part of this specification in which,

Figure 1 is a part side elevation and part longitudinal section of a reversing counter shaft with a friction clutch at each end; Fig. 2 is a cross section of the same taken on line 2-2 of Fig. 1; Fig. 3 is a cross section on line 3-3; Figs. 4, 5 and 6 are enlarged axial sections showing the clutch actuating part in different positions; Fig. 7 is a cross section on line 7-7 of Fig. 1; Fig. 8 is a detail view showing the connection between the clutch actuating part and the rotating quill; Fig. 9 is a diagram of the electrical circuit for energizing the magnets; Fig. 10 is a part elevation and part axial section of a modified form of my clutch applied to a motor drive; and Fig. 11 is a detail view of the clutch actuating part thereof.

In the construction shown in Figs. 1 to 8 there are two clutch pulleys 1 and 2 adapted to be positively driven in opposite directions, a centrally located cone pulley 3 adapted to be coupled with either of the driving pulleys 1, 2, clutch actuating solenoids 4 and 5 disposed on opposite sides of the driven cone pulley 3 and hangers 6 and 7 by which the device is supported from a fixed support. The clutch pulleys 1, 2 are made cup-shape with conical internal peripheries 8 which serve as friction surfaces and are freely journaled upon a tie rod 9 provided at its ends with thrust collars 10. The open side of each of the pulleys is closed by a disk 11 connected thereto by screws 12 and rigidly connected by means of a key 13 to a quill 14 journaled in a bearing 15 on the hanger. A hollow shaft 16 journaled in quills 14 extends nearly the entire length of the tie rod 9, and has rigidly connected to each end a male clutch member 17 with a conical periphery 18 adapted to make frictional contact with the internal periphery 8 of the driving pulley when the shaft 16 is moved axially. The driven cone pulley 3 is loosely mounted upon the center of the hollow shaft 16 but held from axial movement therewith by screws 19 carried by the hub 20 of the pulley, extending through longitudinal slots 21 in the shaft and engaging at their inner ends a peripheral groove 22 turned in the middle of the tie rod 9.

The clutch actuating solenoids 4, 5 are car-

ried in circular grooves formed in the enlarged inner ends of the bearings 15. The solenoid armatures 23, 24 are disk-shaped and each is rigidly connected to an axially movable sleeve 25 mounted on the hollow shaft 16 and having at its outer end, as shown in Fig. 8, longitudinal slots 26 for engaging feather projections 27 on the inner end of the adjacent quill 14 so that it may move freely in an axial direction but is positively rotated with the quill.

On the internal periphery of the enlarged inner ends of the bearings 15 are rigid cam or wedge-shaped projections 28, and on the external peripheries of the sleeves 25 are corresponding projections 29 which, when the sleeves are in retracted positions, see Fig. 1, travel out of the path of the fixed projections 28, but upon excitation of a solenoid its armature is drawn thereto so that the point of the revolving projections 29 on the armature crosses the plane in which the point of the stationary projection 28 lies, see Fig. 4, and further axial movement of the sleeve 25 is effected by the wedging action of the projections 28 and 29 upon each other as the latter is carried past the former by its connection with the power driven part, see Fig. 5.

In order to transmit the axial movement of a sleeve 25 to the hollow shaft 16 after the former has been moved freely by its solenoid to bring the projection 29 into operative position with relation to projection 28, the inner end of the sleeve is provided on its internal periphery with lugs 30 which travel in a groove 31 turned in the periphery of the hollow shaft 16 and having a width in excess of the width of the lugs corresponding to the free axial movement of the sleeve so that at the end of the free movement of the latter, lugs 30 will engage the opposite shoulder of the groove 31 and cause the shaft 16 to thereafter partake of the axial movement of the sleeve.

Each sleeve is normally pressed away from its solenoid by a helical spring 32 surrounding the inner end of the corresponding quill 14 and abutting at one end against the bearing 15 and the other against the flanged end 33 of the sleeve 25.

When it is desired to uncouple the clutch excitation of the solenoid is discontinued and the armature moves away therefrom under the recoil of the spring 32 sufficiently to carry the leading point of projection 29 to the opposite side of the plane of the leading point of the stationary projection 28, see Fig. 6, and the wedging action of the projections upon each other operates to force the hollow shaft and the parts carried thereby into inoperative position.

The diagram of circuit connections for the solenoids is as shown in Fig. 9. It is apparent that by throwing the three point switch

33 to the right or left the corresponding solenoid 5 or 4 will become energized so that the counter shaft rotates in one direction or the reverse, and whenever the switch is moved to central position the counter shaft is brought to rest.

In the differential motor drive construction shown in Figs. 10 and 11 the motor shaft 41 has fixed thereon two pinions 42, 43 of different sizes, which mesh with gears 44 and 45 mounted loosely between thrust collars 46 upon a shaft 47 journaled parallel to shaft 41. The gears 44 and 45 have conical friction surfaces 48 on the internal peripheries of their rims, and fixed to the shaft 47 between gears 44 and 45 is a male clutch member 49 having two friction surfaces 50, 51 adapted to coöperate respectively with the friction surfaces 48 on the gears 44, 45 according to which gear is moved axially thereto.

The means for axially moving each of the gears 44, 45 consists of toggle links 52, 53 pivotally connected together and respectively to a lug 54 on the hub of the gear and a slip band 55 carried in a groove in the thrust collar 46. At the knuckle joint of the links 52, 53 is connected an actuating slide 56 which is carried in a groove in a spoke of the gear where it is held in place by cross bars 57 and the upper end is folded over so as to frictionally engage the outside of said bars 57 and 58 provided with a cam or wedge-shaped projection 58. Within the range of travel of the projection 58 is a stationary projection 59 carried by an arm 60 pivoted to the frame of the machine and movable up and down across the leading point of the projection 58 and resting at the ends of its movement against fixed stops 61, 62 so that when the stationary projection 59 is in lowered position against stops 61 the rotating projection 58 will pass thereover and be raised into elevated position as shown in Figs. 10 and 11 to disengage the gear from the driven clutch member 49, and when the projection 59 is raised against the upper stop 62 the rotating projection 58 will pass thereunder and be forced down so as to straighten the knuckle joint and force the driving gear into engagement with the driven member 49. The arms 60 may be operated by magnets 63 and gravity. The diagram of electrical connections will be the same as shown in Fig. 9.

I do not desire to restrict myself to the particular form or arrangement of parts herein shown and described, since it is apparent that they may be changed and modified without departing from my invention.

What I claim as new and desire to secure by Letters Patent of the United States, is,—

1. The combination with the driving and driven members of a clutch, of an actuating part rotated by said driving member, stationary means for deflecting said part from

its path of rotation, and means for transmitting the deflected motion of said part to one of the clutch members.

2. The combination with the driving and driven members of a clutch, of an actuating part rotated by said driving member, stationary means for deflecting said part from its path of rotation, and means for transmitting said deflected motion to one of the clutch members to effect an axial movement thereof.

3. The combination with the driving and driven members of a clutch, of an actuating part positively connected to said rotating member, stationary means for deflecting said actuating part from its path of rotation, and means for transmitting said deflected motion to one of the clutch members.

4. The combination with the driving and driven members of a clutch, of an actuating part positively driven by said driving member, a stationary device adapted to deflect the actuating part, means for bringing said device and actuating part into engaging relation, and means to transmit the deflected movement of the actuating part to one of the clutch members.

5. The combination with the driving and driven members of a clutch, of an actuating part having an engaging projection and positively rotated by the driving member, a stationary engaging part adapted when brought into the path of said projection to move the actuating part, means whereby the engaging parts may be freely adjusted relatively to each other, and means for transmitting the deflected motion of the actuating part to one of the clutch members.

6. The combination with the driving and driven members of a clutch, of an actuating part positively driven by said driving member, a stationary device, adapted to engage

said actuating part and deflect it axially, and a connecting member between said actuating part and one of the clutch members whereby the axial movement of the former produces a corresponding movement of the latter.

7. The combination with the driving and driven members of a clutch, of an actuating part positively rotated by said driving member and free to move transversely, a stationary device adapted to engage said actuating part to effect its transverse movement, and a shaft having operative engagement with said actuating part and carrying the driven member of the clutch.

8. The combination with the driving and driven members of a clutch, of an actuating part positively rotated by the driving member and free to move axially, a stationary device adapted to engage said actuating part to effect its axial movement, and a shaft connected by a lost motion arrangement with the actuating part and carrying the driven member of the clutch.

9. The combination with the driving and driven members of a clutch, of an actuating part rotated by the driving member and free to move axially, a wedge-shaped projection carried by said part, a stationary projection adapted to engage the wedge-shaped projection to effect axial movement of the actuating part, a shaft connected by a lost motion arrangement with said actuating part and carrying the driven member of the clutch, and means for moving said actuating part to engage upon one side or the other of the stationary projection.

In witness whereof, I have hereunto set my hand this thirty first day of October 1905.
